UNITED STATES PATENT OFFICE.

WILLIAM C. NORCROSS, OF TERRE HAUTE, INDIANA.

LEVELING DRAWING-TABLE FOR COMBINATION JOLT-RAMMING AND ROCK-OVER MACHINES.

1,245,953.

Specification of Letters Patent.

Patented Nov. 6, 1917.

Application filed October 21, 1916. Serial No. 126,845.

To all whom it may concern:

Be it known that I, WILLIAM C. NORCROSS, a citizen of the United States, residing at Terre Haute, county of Vigo, and State of Indiana, have invented certain new and useful Improvements in Leveling Drawing-Tables for Combination Jolt-Ramming and Rock-Over Machines, of which the following is a specification.

10 This invention relates to leveling drawing tables for combination jolt-ramming and rock-over machines and is an improvement on the leveling drawing table set forth in my Patents No. 1224407, dated May 1, 1917 and No. 1231187 dated June 26, 1917.

15 Machines of the general class to which my invention belongs embody an automatic jolt-ramming machine, and drawing cylinder having a table to support the mold as it is lowered away from the pattern, rock-over means being used to tilt the rammed flask, mold, pattern, and attachments to a position where the mold may be lowered away from the pattern.

20 In this class of machines, it is important to provide a suitably level and firm bearing or support for the mold while it is being drawn from the flask and pattern for, unless supported perfectly level, there will be a tendency to distort the mold as it will not draw clear from the pattern without relative lateral movement.

25 In my patents aforesaid I have shown and described and in the latter of said patents have claimed, a novel leveling table or attachment for the drawing cylinder which is adapted to automatically adjust itself, on elevation of the piston of the drawing cylinder, by its contact with the bottom board or the battens thereof, after the rammed mold has been rocked-over. That drawing table has improved means whereby it may be securely fastened in its set or adjusted position, such fastening being necessary inasmuch as the table is pivotally or oscillatorily supported in the region of its central portion.

30 The object of the present invention is the provision of an improved leveling drawing table which upon adjusting itself to inequalities of the bottom board or the battens thereof, is held in that position by friction between itself and its supporting means caused by the weight of the mold resting

upon said table, thus obviating the necessity 55 of employing a locking means which requires attention on the part of the operator. The cost of manufacture and the time required to draw a mold are both greatly lessened by my improvements while, at the same 60 time there is no possibility of the mold being distorted.

My invention contemplates the provision of a leveling drawing table which is tiltably mounted so that it will conform to the bottom board or the battens thereof and, when the mold is supported by the table, the pressure or weight of the mold will cause the table to be frictionally held upon its support 65 without resort to any locking device. 70

The table has a plurality of supporting or bearing surfaces or devices on which the mold rests. Modifications may be resorted to in the manner of supporting or mounting the table. The invention may be otherwise 75 changed. Consequently, I do not limit myself to the precise construction hereinafter described and shown in the accompanying drawings as such construction is to be considered as illustrative, rather than restrictive, of the scope of the invention. 80

In the accompanying drawings:

Figure 1 is a side elevation of the drawing table, certain parts being broken away;

Fig. 2 a plan view thereof;

Fig. 3 a side elevation, partly broken away, of a modification, and

Fig. 4 a plan view thereof.

Referring first to Figs. 1 and 2, 1 is the cylinder of the drawing table and 2 the piston working therein. Any suitable means may be provided for lifting the piston as, for instance, compressed air. The drawing table may be elevated and depressed mechanically and the cylinder dispensed with, if preferred, in which event the raising and lowering means would be applied to the support 2. 90 95

The upper end of the support 2 has a ball 3. The drawing table comprises a plurality of sections 4 which have a plurality of bearing or supporting parts 5. The mold, not shown, is adapted to rest upon the bearing parts 5 when the support 2 is elevated to bring the table against the bottom board or the battens thereof of the mold which has been rammed and rocked-over, or otherwise positioned for drawing. The in- 100 105

ner ends of the sections 4 have concavities 6 which embrace and bear upon the ball 3. The upright flanges 7 on the sections 4 are connected, above the ball 3, by a bolt 8 whose heads or head and nut 9 and 10, bear upon the outer faces of said flanges and are preferably rounded or formed to fit in corresponding concavities in the flanges as shown at 11. The space 12 which exists between the flanges 7 enables the sections 4 to relatively move and to have a gripping action on the ball 3 when pressure is applied to said sections by the supporting of the mold thereby. The employment of the ball 3 and the concavities 6 enables the sections 4 to tilt and twist, in a universal manner, so that when the support 2 is elevated and the bearing points or parts 5 engage the bottom board or battens on the mold, the table will automatically conform to the position of the mold. When the support 2 is lowered, to draw the mold from the pattern, the weight of the mold acting on the parts 5 causes them to exert a leverage so that the faces of the concavities 6 bear firmly and frictionally upon the ball 3 and the table is thus automatically held, by frictional engagement, to the support 2. No other locking means is employed to hold the table in its adjusted position.

Referring to Figs. 3, 4, instead of the table being formed in a plurality of sections, it is in a single integral or rigid piece 13 which has arc-shaped flanges 14 of suitable length, say 90°, more or less. Carried by the piston 2 is a head 3^a which is a truncated semi-sphere, or spherical section, of relatively large diameter, on which the concave surfaces or edges 14^a of the flanges 14 frictionally bear. Being of relatively large diameter, the head 3^a provides a sufficiently large support and superficial area so that the weight of the mold supported on the table 13 causes such frictional contact as will hold the table in the position it has assumed when it engages the mold. The one piece table 13 has three bearings or mold supporting points or surfaces 5^a.

I wish it understood, however, that I do not limit myself to the number of bearing

points 5 or 5^a, that is, the number of points adapted to engage the mold.

In both forms of the invention, the connection between the table and its support, is of the nature of a ball and socket joint, constituting a friction lock which holds the table where set when the mold rests on the table, as the center of gravity is about central with the said ball and socket support. 55

Having thus described my invention, what I claim as new and desire to secure by Letters Patent, is:

1. A self-locking leveling drawing table comprising a plurality of relatively movable connected mold-supporting sections, 65 and a support, common to said sections, with which said sections collectively engage.

2. A self-locking leveling drawing table comprising a plurality of relatively movable connected mold supporting sections collectively provided with a cavity, and a rounded support, common to said sections, said support being received in said cavity and said sections frictionally engaging said support. 70

3. A self-locking leveling drawing table comprising a pair of table sections hinged together, and a support with which said sections collectively engage.

4. A self-locking leveling drawing table comprising mold-supporting sections, loosely articulated together, and a support, common to said sections, with which they collectively engage. 80

5. A self-locking leveling drawing table comprising relatively movable sections, a loose connection between the inner end portions of the sections, and a frictional support, common to the inner end portions of said sections. 90

6. A self-locking leveling drawing table comprising relatively movable sections having cavities in their inner end portions, a loose connection between the inner end portions of the sections, and a rounded support received in the cavities aforesaid, with which said sections frictionally engage. 95

In testimony whereof, I hereunto affix my signature.

WILLIAM C. NORCROSS.
